UNITED STATES PATENT OFFICE

137,305

DESIGN FOR A WINDOW FRAME

Percy K. Hosken, Wharton, N. J.

Application May 17, 1943, Serial No. 110,218

Term of patent 3½ years

To all whom it may concern:

Be it known that I, Percy K. Hosken, a citizen of the United States, residing at Wharton, in the county of Morris and State of New Jersey, have invented a new, original, and ornamental Design for a Window Frame, of which the following is a specification, reference being had to the accompanying drawing, forming part thereof.

Figure 1 is a front elevational view of a window frame showing my design; and

Figure 2 is a side elevational view thereof.

I claim:

The ornamental design for a window frame, as shown.

PERCY K. HOSKEN.
